UNITED STATES PATENT OFFICE.

HARRY ROSENTHAL, OF NEW YORK, N. Y.

PERPETUAL CALENDAR.

Application filed December 24, 1921. Serial No. 524,683.

To all whom it may concern:

Be it known that I, HARRY ROSENTHAL, a citizen of the United States, residing at New York city, borough of the Bronx, in the 5 county of Bronx and State of New York, have invented certain new and useful Improvements in Perpetual Calendars, of which the following is a specification.

This invention relates to stationery and 10 has particular reference to calendars or other analogous devices intended for use on walls, desks, or other places and capable of being used for advertising purposes or the like, as well as for usual calendar purposes.

15 Among the objects of the invention is to provide a calendar comprising a relatively rigid body having characteristics adapting it for use for an indefinite number of years and so constructed as to maintain not only 20 its form but neat and sanitary appearance and having associated with the body one or more movable members so adjustable with reference to the body as to always indicate the month and the day of the month in connection with characters showing the days of 25 the week.

A further and more specific object of the invention is to provide a perpetual calendar having a relatively rigid or stationary body 30 fitted with one or more movable or adjustable members with means for shifting said members, but having no parts projecting beyond the surface or edges of the body, whereby it is impossible for the device to become 35 disarranged or out of adjustment.

With the foregoing and other objects in view the invention consists in the arrangement and combination of parts hereinafter described and claimed, and while the invention is not restricted to the exact details 40 of construction disclosed or suggested herein still for the purpose of illustrating a practical embodiment thereof reference is had to the accompanying drawings, in which like 45 reference characters designate the same parts in the several views, and in which—

Figure 1 is a face view of one form of my improvement.

Fig. 2 is a rear view of the same.

50 Fig. 3 is a vertical section on the line 3—3 of Fig. 2.

Fig. 4 is a face view of the movable slide.

Referring now more specifically to the drawings I show a body 10 of rectangular 55 form and made preferably of any suitable relatively rigid and strong durable material.

While this body is shown as of flat rectangular form it is obvious that the spirit of the invention would not be violated if any other form were adopted. The body is 60 formed in its face, as indicated, with two windows 11 and 12 for the purpose of the display respectively of the name of the month and a group of figures suitably arranged in connection with names corresponding to the month so named and representing the days of the week and of any suitable design. Obviously these windows may be of any desired shape or relative size and may be located at any places with respect to 70 the face of the body, the remainder of the face of the body being adaptable for ornamentation, advertising, or other display purposes. In fact the body itself might consist of or constitute a paper weight, box cover, or 75 other device adapted for utility along other lines than solely as a calendar.

Located back of the window 11 is a movable member indicated as a disk 13 secured in place by means of a hollow rivet or eyelet 80 14 or by any other means having an inconsiderable amount of thickness to be added to the thickness of the body. In other words, the disk 13 is secured within the body by means adapting it for rotation around its 85 center and having no parts projecting beyond the plane of the front and back of the body nor beyond the edges thereof. This disk 13 has printed or otherwise formed on its front face a circular concentric series of 90 legends naming or representing the twelve months of a year together with the number of days in the respective months, the name of one and only one and its number of days being observable through the window 95 11. Since the designations for the months and the days of the months are visible only within or back of the window 11 it is plain that not only will the disk be immovable by accidental contact therewith through the 100 window but also the disk itself will be kept clean and neat by virtue of the protection afforded by the front portion of the body.

With the member 13 in the form of a disk adapted for rotation around a fixed center, 105 said disk may be divided on its surface into twelve equal sectors pertaining to the several months of the year. Means is provided for the movement of this disk once around its center through exactly twelve successive 110 steps or spaces and so that the several names of the months will be caused to ap-

pear in a definite position through the window 11 without any special care or attention on the part of the operator who may be making the adjustment thereof at the beginning of each month. To this end I form in or on the back of the disk a series of twelve equally spaced holes 15 arranged concentrically of the pivot 14. Between these in regular order around the series are the names or abbreviations of the names of the several months. In the back wall of the body is formed an opening 16 with which the holes and monthly designations are adapted to register in succession, the length of the opening 16 in the direction of the series of holes being exactly equal to the distance between the opposite sides of two adjacent holes. Hence by inserting a pencil point, a match stick, tooth pick, or any other relatively sharp instrument into either hole 15 the operator may move the disk through one step only, the movement being stopped by the striking of the instrument against the opposite end wall of the opening 16. Thus the disk will be moved far enough to effect the adjustment for exactly one month at each operation. An arrow may be indicated on the back as at 17 to guide the operator as to the direction the disk should be moved from one month to the next. The monthly designations on the front and rear faces of the disk are so correlated to each other and the window 11 and opening 16 that when the adjustment is effected at the back as desired, the indication at the window 11 will be consistent therewith. The radius of the circle of holes may be the same or greater or less than the radius of the circle of the names of the months visible through the window 11.

Associated with the window 12 are names or characters representing the days of the week from Sunday to Saturday inclusive as indicated at 18. Within or back of the window 12 is a slide 19 having on its face groups of numerals arranged to show the days of any month when the slide is adjusted suitably with respect to the days of the week. With the days of the week indicated in a horizontal direction the numerals on the slide are similarly arranged in horizontal lines on the face of the slide in selective groups, each group comprising seven vertical columns relative to the days of the week. The grouping of these numerals is such that any one group may fill the window 12, exclusive of all surplus numbers on the slide, and the slide is adjustable or movable in such a manner as to bring the numeral for the first day of the month below any one of the names of the days of the week along the series 18, and when so adjusted the group of days of the month will be exclusive just the same as in any monthly sheet 65 of a calendar pad. In other words, the slide

19 is longer than the window 12, and it has at either or both ends additional vertical rows of numerals, which in turn may be made parts of the grouping of the numerals as aforesaid, according to the adjustment of 70 the slide.

20 indicates an opening in the rear wall of the body 10 exposing the rear surface of the slide to view, and registering with the opening 20 are a series of holes 15' similar to the holes 15 above described, the length of the opening 20 being exactly equal to the distance between the remote sides of each two adjacent holes 15'. For each pair of holes, and shown between them, is the name or abbreviation of a day of the week. The names or abbreviations are arranged in regular order, and the construction of the slide is such that when the slide is adjusted so as to bring the numeral "1" on the face of the slide in registry with any selected day of the week, according to the calendar for the current month, the name or abbreviation visible at the opening 20 will show the corresponding day of the week. In the adjustment of 90 the calendar at the beginning of each month the operator has but to insert a relatively sharp pointed instrument into either hole 15' visible at the time and so move the slide step by step until he sees the desired day of the week registering with the opening 20. The instrument will always be stopped exactly at the end of each predetermined step by contact with the end wall of the opening 20 toward which it is moved, thereby insuring that the face of the slide visible in the window 12 will always have proper adjustment as to the edges of the window. The slide may be moved as many steps for each adjustment as the circumstances will demand, 105 but at the time of final adjustment proper registry will be insured. It will thus be seen that I provide a movable member, carrying the names of the months and their corresponding numbers of days and also another 110 movable member carrying selective groups of numbers of days of the month to be adjusted with respect to the days of the week, and that the adjustment of either of these members is effected through means inserted 115 within the body of the device thus insuring that there are no projecting parts to be inadvertently touched or moved and whereby the calendar thus constructed will always be dependable. It is furthermore noteworthy 120 that no special care on the part of the operator is necessary in making the adjustment of either member as to stopping the same at the precise point for proper registry through the main front windows.

I claim:

1. In a perpetual advertising calendar the combination with a stationary body, having a display-opening in its front face for the month announcement, and another display 130

- opening for the successive week-days, marked in permanent characters on said body and in juxtaposition to this opening, and a member rotatably attached to said body, bearing upon its front face a series of indicia referring to the successive months and successively visible through the first mentioned display-opening; of an element, movably attached to said body and bearing on its front face series of ordinals from 1 to 31, combined in such a manner, that when the element is moved step by step, corresponding to the intervals between centers of adjacent ordinals, relatively to the stationary body, the display-opening for the week days will successively show all possible actual combinations of these ordinals in reference to the week day characters, placed in juxtaposition and registering with the exposed portion of the serial numbers, means, disposed at the rear of said stationary body, for moving the rotatable member step by step corresponding to the intervals of the indicia indicated thereon, and means, disposed at the rear of said stationary body, whereby when the above mentioned element is moved through one step it is compelled to stop at the precise point where the next successive combination of ordinals is visible in the display opening for the week days.
2. In a perpetual advertising calendar the combination with a relatively rigid and stationary body, having a display opening in its front face for the month announcement and another rectangular display-opening, registering with an index of the week days, inscribed on the body alongside of it, and a disk, rotatably attached to said body, bearing upon its circumference a serial index of the months and successively visible through the first mentioned display-opening; of a slide, movably engaged with and substantially protected by its disposition within said stationary body and bearing on its front face series of ordinals from 1 to 31, combined in such a manner, that when the slide is moved step by step, corresponding to the intervals between centers of adjacent ordinals, relatively to the stationary body, the display-opening for the week days will successively show all possible actual combinations of these ordinals in reference to the week day characters, registering with the exposed portion of the serial numbers, means, disposed at the rear of said stationary body for moving the rotatable member step by step, corresponding to the intervals of the indicia indicated thereon, and means, disposed at the rear of said stationary body, whereby when the above-mentioned slide is moved through one step, it is compelled to stop at the precise point where the successive combination of ordinals is visible in the display-opening for the week days.
3. In a perpetual advertising calendar the combination with a stationary body, having a display-opening in its front face for the month announcement and another display-opening, registering with an index of the week days, inscribed on the body alongside of it, and a disk, rotatably attached to said body, bearing upon its circumference a serial index of the months and successively visible through the first mentioned display-opening; of a slide, movably engaged with said stationary body and bearing on its front face series of ordinals from 1 to 31, combined in such a manner, that when the slide is moved step by step, corresponding to the intervals between centers of adjacent ordinals, relatively to the stationary body the display-opening for the week days will successively show all possible actual combinations of these ordinals in reference to the week day characters, registering with the exposed portion of the serial numbers, means, disposed at the rear of said stationary body for moving the rotatable member step by step, corresponding to the intervals of the indicia indicated thereon, and means, disposed at the rear of said stationary body for moving the rotatable member step by step, corresponding to the intervals of the indicia indicated thereon, and means, disposed at the rear of said stationary body, whereby when the above-mentioned slide is moved through one step, it is compelled to stop at the precise point where the successive combination of ordinals is visible in the display-opening for the week days.
4. The combination with a perpetual advertising calendar, formed as set forth in claim 1, and having an element, movably attached to said calendar, for the display of successive combinations of monthly ordinals, as described in said claim; of means, disposed at the rear of the calendar, for moving said elements step by step through the successive combinations, and means to indicate by a display-opening, attached to the rear of the calendar, and an index, attached to the rear of above said element, the simultaneous relative positions of the ordinals, as displayed on the front of the calendar, when said element is moved step by step.
- In testimony whereof I affix my signature.

HARRY ROSENTHAL.
